LOCK MECHANISM FOR INSULATED FILING CABINETS

Carl W. Wikman, Muskegon, Mich., assignor to
Shaw-Walker Company, Muskegon, Mich., a
corporation of Michigan

Application June 15, 1946, Serial No. 677,005

4 Claims. (Cl. 109—53)

1

This invention relates to a lock mechanism for fire resisting filing cabinets and safes, and has for its principal object to provide an improved mechanism of the character described consisting of a controlling connection between the interior latching mechanism and a lock device accessible from the exterior of the cabinet casing, which is capable of being installed without substantial weakening of the insulated walls of the casing, and affords a minimum conduction of heat from the exterior to interior through the metallic control member which must pass through the insulation.

On present types of insulated filing cabinets and safes, the locking mechanism itself usually passes through the entire insulated wall thereby allowing heat to be readily conducted into the interior of the casing and so shortening the length of time the cabinet will protect its contents during a fire. Heat also passes through the insulated walls of the cabinet more readily at any points which have been reduced in thickness in order to accommodate the locking mechanism.

In carrying out my invention I provide a flexible control wire and tubular housing which is molded in the insulation so as to pass through the latter, thus presenting a highly restricted path for conduction of heat to the interior of the cabinet.

A further feature of my invention is the provision of a locking bar on the interior of the casing for operating a plurality of latches in the several drawer compartments of the cabinet, which locking bar is so designed as to displace a minimum amount of insulating material in the side wall of the cabinet.

A still further feature of the invention is the provision of the necessary levers for operating the several spring latches for the drawers and the like, which levers and associated parts are so disposed and mounted that they do not materially displace or weaken the insulation in the exterior walls of the cabinet.

The invention may best be understood by reference to the accompanying drawings, in which:

Figure 1 is a vertical section of an insulated filing cabinet having a plurality of drawer compartments, illustrating one embodiment of my invention in which the locking bolt is disposed in the top sill of the cabinet.

Figure 2 is an enlarged fragmentary view showing details of the lock and the latch mechanism in the top drawer compartment of the cabinet shown in Figure 1.

Figure 3 is a detail section taken generally on

2

line 3—3 of Figure 2, with part of the insulation broken away to show an anchoring support.

Figure 4 is a detail section taken on line 4—4 of Figure 2.

5 Figure 5 is a horizontal section showing a modified form of lock mechanism, in which the locking bolt is located in the stile of the cabinet, and the several drawer latches are controlled through a vertical torsion shaft instead of a reciprocating bar, as in the form shown in the foregoing figures.

10 Figure 6 is a detail side view of the locking mechanism of Figure 5, with the insulation removed from the casing to show the arrangement of the working parts of the lock, latch control levers, and the metal mountings therefor on the interior of the casing.

15 Figure 7 is a fragmentary front view showing details of the stile of the cabinet broken away to show parts of the drawer support and one side of the drawer in the cabinet.

20 Figure 8 is a detail section taken on line 8—8 of Figure 6.

25 Referring now to the embodiment of my invention illustrated in Figures 1 to 4 inclusive, a filing cabinet indicated generally at 10 consists of top and bottom walls 11, 12, a rear wall 13, side walls 14 and intermediate horizontal partitions 15, 15 dividing the cabinet into a plurality of drawer compartments. The cabinet walls consist as usual of a sheet metal casing 16, with an insulating lining 17 of fire resisting material such as gypsum, preferably molded in the outer casing. The horizontal partitions 15, 15 are also of molded insulating material. Drawers 18, 18 are of the usual sheet metal construction each having a head 19 formed of sheet metal, with an insulating filler 20. The drawer heads each have the usual flanged side margins 21 adapted to fit in grooves 21a formed in the stiles 22 of each drawer opening, and also have flanged top and bottom margins 23 adapted to fit in similar grooves 24 formed in the top and bottom sills of each drawer frame opening, to provide a heat resisting seal for the drawer head in each compartment.

30 35 40 45 The body of each drawer includes, as usual, a bottom wall and side walls. The drawers may also be provided as usual with suitable rollers (not shown), for rolling engagement with metal track rails mounted on the inner sides of the insulating liner.

50 55 It will be understood, however, that the drawer structure is merely shown for purposes of illustration of my improved locking mechanism which can be applied as well to other closed

members such as hinged doors, or a combination of drawers and doors, if desired.

Referring now more particularly to the lock mechanism incorporated in the cabinet, a lock 30 is mounted in a housing 31 embedded in the front edge of the top wall 11. Said lock is of the conventional key controlled type having a bolt 33 at one side adapted for locking engagement as usual in a recess in the lock casing 31. The lock is slideable in its casing and is pushed inwardly to bring the bolt 33 into locking position.

A metal control wire 35 is connected to the inner end of the lock 30 as by a pin 36 passing through an eye 37 at the end of said wire. Said control wire passes through the front end of the lock housing into a flexible tubular sheath 38 preferably made of coiled wire. Said sheath, with the wire enclosed, is trained inwardly through the adjacent insulating liner 17, and thence downwardly in an arcuate path into the upper drawer compartment along one side thereof. The inner end of the sheath is fixed by nuts 39, 39 to a bracket 40 forming part of a support plate 41 fixed along the inner face of the compartment.

A rocking lever 42 is pivotally mounted on a stub shaft 43 projecting inwardly from the support plate 41. The inner end of the control wire 35 is passed through a transverse aperture 45 in a pin 46 on the end of said lever, and is engaged in said pin by a set screw 47, to permit endwise adjustment of the wire when necessary. The pin 46 is preferably mounted for rotation on the rocking lever 42.

Spring means are provided for normally urging the lock 30 in unlocked position, as herein shown said means consisting of a coil spring 44 connected between the bracket 40 and the adjacent end of the rocking lever 42.

The opposite end of the rocking lever 42 is pivotally connected to the top of a vertically disposed lock bar 50 by a pin 51 extending through a vertically disposed slot 48 in the cover plate 54 and projecting into a transversely disposed slot 49 formed in said lock bar, as shown in Figure 3, which bar extends downwardly substantially the full height of the cabinet for controlling individual drawer latches in each compartment. Said lock bar is formed of a relatively thin strip of metal, and is guided in a metallic sheath member 52, which is embedded flatwise along the adjacent side wall of the cabinet so as to encroach but a limited depth upon the thickness of the insulating liner. The sheath member 52 is formed of sheet metal, of substantially U-shape in cross section, to form a relatively flat groove for the lock bar, and also has extended flanges 53 along opposite sides thereof.

A cover plate 54 of sheet metal, extends along the outer face of the sheath member 52 to confine the lock bar closely for vertical movement therein, while restraining said bar from bowing or bending when endwise pressure is exerted thereon.

In the form shown the cover plate 54 overlaps the extended flanges 53, 53 of the sheath member 52, and is bent inwardly beyond said sheath flanges to terminate in angled flanges 55, 55 which form anchors within the body of the insulating material as shown in Figure 3. In this manner the lock bar and its sheath consisting of plates 52 and 54 may be made of minimum thickness, so that they encroach a

limited amount upon the thickness of the insulating liner in which said sheath is embedded.

In practice, the several metal supporting parts including the lock housing 31, tubular sheath 38, support plate 41, and lock bar sheath parts 52 and 54, are all preferably set in position before the insulating liner 17 is molded in the outer casing, so that the fixed metal parts are firmly embedded in said liner to form permanent fixtures therein when the molding is completed. The support plate 41 preferably extends through a cut-away portion of the cover plate flange 55, and is secured as by welding to the inner side of flange 53 of the inner sheath member 52 before the parts are molded in place. The support plate 41 also is provided with a pair of outwardly extending flanges 57, 57 forming anchor members extending into the insulating liner as shown in Figure 3.

Referring now to the latch devices for the individual drawers 18, 18, a strike lever 60 is mounted on each horizontal partition member 15, 15 forming the bottom of a drawer compartment in position to engage an overhead lock strike 61 fixed to the bottom wall 25 of each drawer. Each strike lever is pivotally supported on a horizontally disposed lever shaft 63 having bearing at opposite ends of the upright wings 64, 64 of a supporting bracket 65. Said supporting bracket is mounted on a base plate 66 which is recessed in a pocket 67 formed in the upper face of its respective horizontal partition 15 adjacent the side wall 14 along which the lock bar 50 and its guide sheath extend, as shown in Figure 2 and 4.

In the preferred form shown the base plate 66 has marginal side flanges 68 and end flanges 69, and the inner side flange 68 is preferably secured as by welding to the outer face of the cover plate 54 of the lock bar guide sheath, as seen in Figure 4.

The strike lever 60 is normally held under tension by a latch spring 70 coiled around the lever shaft 63 with one terminal end engaging the support bracket 65 and the other terminal end engaging the under face of said strike lever. Movement of said strike lever is limited and controlled by a latch lever 73 fixed on the outer end of the lever shaft 63 and having an inturned lug 74 extending over one side of the strike lever to engage its upper edge. Movement of the latch lever is controlled by an actuating lever 75 fixed on the inner end of said lever shaft and having a pin 76 at its outer end extending through a vertical slot 77 in the cover plate 54 and into a transversely extending slot 79 in the lock bar 50. (See Figure 4)

With the arrangement just described the latch lever 73 forms a stop against which the strike lever 60 is normally engaged under tension of the latch spring 70 in position to engage the lock strike 61 on the adjacent drawer bottom 25, but said strike lever is free to be depressed against the tension of its spring so when the lock strike is moved along the top of said strike lever in a direction to close the drawer, said strike lever will be depressed until the lock strike passes its inner end, whereupon the strike lever will move upwardly into latching position. When the drawer is to be unlocked, the lock bar 50 is moved downwardly by releasing the lock 30 on the top stile of the cabinet.

Since said lock is connected by control wire 35 to the rocking lever 42 and is normally urged into unlocking position (as shown in dotted lines

in Figure 2) under tension of the unlocking spring 44 as previously described, all of the drawers are normally unlocked excepting when the lock 30 is moved into locking position (as shown in full lines in Figure 2), in which position the several latches are moved into position to lock the drawers automatically whenever they are fully closed.

In the modified form of locking mechanism shown in Figures 5 to 8, the lock 80 is slidably mounted in its housing 81 disposed in the side sill of the cabinet, and is connected to the latch mechanism on the interior of the casing, as before, by a flexible wire 83 encased in a tubular sheath 84 of coiled wire molded in the insulating material liner 17 of the side wall of the cabinet. The drawer 85 is provided with a lock strike 86 on the adjacent side wall thereof, instead of on the bottom of the drawer as in the form previously described in connection with Figures 1 to 4 inclusive.

The inner end of the flexible control wire 83 is secured to a pivoted pin 87 on one end of a rocking lever 88, fixed on the upper end of the upright shaft 89. The opposite end of the rocking lever 88 has a pin 89^a engaged in the forked end 90 of a latch lever 91. Said latch lever is pivoted intermediate its ends on a pin 92 fixed on a support bracket 93 projecting inwardly from the side wall of the cabinet. A strike lever 94 is also pivotally mounted on the pivot pin 92 adjacent the latch lever, and is provided with spring means normally urging it inwardly toward the drawer 85, said spring means herein consisting of a spring 95 coiled around the pivot pin 92, with its free end engaging the outer edge of said strike lever.

The strike lever 94 has an upwardly projecting lug 96 adapted to be engaged by the free end of the latch lever 91 when the latter is swung outwardly away from the drawer so as to move the strike lever out of the path of the lock strike 86 on the side of said drawer.

The several parts of the latch mechanism above described are mounted on a support plate 99 which is fixed to the inner face of the insulating liner 17 and also forms a support for an inwardly extending guide rail 100 adapted to be engaged by supporting rollers (not shown) forming part of the usual drawer extension slide. A portion of the insulating liner 17 is cut away to form a shallow recess 101 in the insulating material, to provide the necessary clearance for movement of the rocking lever 88 and the latch lever 91. The support plate 99 has an outwardly turned flange 102 along its upper margin. A bearing plate 103 is fixed to the top of said bearing plate flange 102 and has the upper end of the control shaft 89 journaled therein. The bracket 93 which has the latch lever 91 and strike lever 94 pivoted thereon, is also fixed to the support plate 99 as by welding to the rear face of the latter.

Spring means are provided for normally holding the rocking lever 88 in unlocked position, as herein shown, said means consisting of a spring 104 connecting the end of lever 88 to a bracket 105 suitably fixed to the side wall, so as to urge said lever into position to unlock the latch mechanism.

The upright control rod 89 extends downwardly in a relatively small groove formed along the insulating material as indicated at 106 in Figure 8. This control rod extends downwardly to connect with one or more latch devices simi-

lar to that which has been herein described for operating the top drawer 85, so that all of the drawers of the cabinet are controlled simultaneously by the single lock 80.

Thus the several strike levers 94 in the cabinet are normally held in unlocked position by the latch levers 91 until the lock 30 is moved inwardly to locking position against the tension of spring 104. This movement causes the latch lever 91 to swing inwardly and permit the strike lever 94 to move into the path of movement of the drawer strike 86.

It will be understood that the support plate 99 and the lock housing 81 together with the control rod sheath 84 are initially molded in the insulating liner 17 at the time the latter is formed in the casing, and the latch mechanism and lock, together with the flexible control wire 83 are later assembled in their proper operating positions as shown in the several figures.

Although I have shown and described certain embodiments of my invention, it will be understood that I do not wish to be limited to the exact construction shown and described, but that various changes and modifications may be made without departing from the spirit and scope of the invention as defined in the appended claims.

I claim:

1. A fire-resisting cabinet having exterior walls including integrally molded insulating material defining an interior compartment with a framed opening, an insulated closure for said opening, a latch device for said closure recessed in the molded insulation on the interior of one of said walls and including a portion exposed to the interior of said compartment and accessible through said framed opening for connection to a latch locking means, and locking means for said latch device including a lock member recessed in the molded insulation of one of said walls and accessible from the outside of the latter, a tubular sheath permanently embedded in the molded insulation of the latter wall and extending from said lock member toward said latch device, the inner end of said sheath terminating in proximity to said exposed portion of said latch device, and a flexible wire operatively connecting said lock member to said latch device and slidably encased in said flexible wire including an end portion projecting from the inner end of said sheath and accessible through said framed opening for operative connection to the exposed portion of said latch device.

2. A fire-resisting cabinet having exterior walls including integrally molded insulating material defining an interior compartment with a framed opening, an insulated closure for said opening, a latch device for said closure recessed in the molded insulation on the interior of one of said walls and including a portion exposed to the interior of said compartment and accessible through said framed opening for connection to a latch locking means, and locking means for said latch device including a lock member recessed in the molded insulation of one of said walls and accessible from the outside of the latter, a tubular sheath permanently embedded in the molded insulation of the latter wall and extending in an inwardly curved path from said lock member toward said latch device, the inner end of said sheath projecting into said compartment at a point accessible through said framed opening and terminating in proximity to the exposed portion of said latch device, and a flexible wire operatively connecting

said lock member to said latch device and slidably encased in said tubular sheath, said flexible wire including an end portion projecting from the inner end of said sheath for operative connection to the exposed portion of said latch device, said tubular sheath and wire forming the sole metallic connection between said lock member and said latch device for limited conduction of heat through the exterior walls of the cabinet.

3. A fire-resisting cabinet having exterior walls and an interior partition, each including integrally molded insulating material and jointly defining a plurality of individual interior compartments with framed openings, insulating closures for each of said compartments, a latch device for each of said closures recessed in the molded insulating material defining the interior compartments, and locking means for said latch devices including a common control rod recessed along the interior surface of one of said exterior walls and passing through the interior partition defining said compartments, said control rod terminating in a portion exposed to the interior of one of said compartments and accessible through one of said framed openings, a lock member recessed in the molded insulation of one of said walls and accessible from the outside of the cabinet, a tubular sheath permanently embedded in the molded insulation of the latter wall and extending in an inwardly curved path from said lock member toward the exposed portion of said control rod, the inner end of the sheath projecting into said one compartment at a point accessible through said one framed opening and terminating in proximity to the exposed portion of said control rod, and means operatively connecting said lock member to said control rod including a flexible wire slidably encased in said tubular sheath, said flexible wire including an end portion projecting from the inner end of said sheath for operative connection to the exposed portion of the control rod, said tubular sheath and wire

5
10
15
20
25

forming the sole metallic connection between said lock member and said latch device for limited conduction of heat through said last-named wall.

4. A fire-resisting cabinet having exterior walls and a plurality of interior partitions, each including integrally molded insulating material and jointly defining a plurality of individual interior compartments with framed openings, insulating closures for each of said compartments, latch devices for said closures recessed in and supported by said interior partitions, and locking means for said latch devices including a common control rod recessed along the interior surface of one of said exterior walls and passing through the interior partitions defining said compartments, a lock member recessed in the molded insulation of one of said walls and accessible from the outside of the cabinet, a tubular sheath permanently embedded in the molded insulation of the latter wall and extending in an inwardly curved path from said lock member to said control rod, and means operatively connecting said lock member to said control rod including a flexible wire slidably encased in said tubular sheath, said tubular sheath and wire forming the sole metallic connection between said lock member and the interior of said cabinet through said last mentioned wall for limited conduction of heat therethrough.
